LINEAR MOVEMENT RUDDER PEDAL
AND LINKAGE

Edward C. Wells, Seattle, Wash., assignor to Boeing Airplane Company, a corporation of Delaware

Application December 13, 1944, Serial No. 568,031

6 Claims. (Cl. 244—86)

1

My invention pertains to an element movable linearly, and more particularly to airplane rudder pedal mechanism.

The direction of flight of an airplane is customarily controlled by a rudder which is swung by application of force to a pair of rudder pedals on which the pilot's feet rest. These pedals are interconnected so that when one of them is pushed away from the pilot the other moves toward him.

A conventional rudder bar pivoted at the center is disposed exactly athwartships when the rudder is in neutral position. As such rudder bar is swung in either direction to swing the rudder correspondingly away from neutral position the pilot's feet move somewhat sidewise toward a fore and aft line through the rudder bar pivot because of the arc along which the rudder pedals fixed to the rudder bar move, although they travel principally fore and aft. Such sidewise movement decreases the leverage available. The farther the rudder is swung from neutral position, however, the greater are the aerodynamic forces acting upon it which tend to return it to neutral position.

By the use of my arrangement a conventional rudder bar pivoted at its center may be employed, but the rudder pedals, instead of being mounted directly upon this pivoted bar, are connected to it through linkage, and are guided by additional linkage so that in all swung positions of the rudder bar the rudder pedals travel directly fore and aft and the leverage on the rudder bar is therefore constant.

It is a principal object of my invention to provide supporting and guiding mechanism for airplane rudder pedals, or other elements, which will constrain movement of such pedals or elements to a predetermined linear path.

A further object is to control such movement of an element by the use of pivoted linkage, rather than by slide and guide mechanism or other types of structure employed heretofore to effect such motion.

A further advantage of my mechanism is that it can be applied to a conventional type of centrally pivoted rudder bar without requiring the bar mounting structure to be altered appreciably.

Characteristics of my linkage for effecting linear motion generally, and more particularly when incorporated in a rudder pedal mount, will be pointed out hereinafter in the specific description of a preferred form of my invention.

Figure 1 is a side elevational view of airplane rudder pedal mechanism incorporating my inven-

tion. Figure 2 is a plan view of such mechanism with a portion of it broken away.

Figure 3 is a cross-sectional view taken through a rudder pedal journal on line 3—3 of Figure 2.

Figure 4 is a cross-sectional view through the central portion of the rudder bar and its mounting along line 4—4 of Figure 2.

The principles involved in the mechanism for supporting and guiding the rudder pedals to be described hereinafter may be incorporated in mechanism of various types, and may take a variety of forms. The general construction and characteristics of such mechanism will be discussed in connection with the specific application to the airplane rudder pedal mounting illustrated in the drawing.

The upright tubular shaft 1 may be connected in conventional fashion to the rudder so that rotation of tube 1 about its axis will swing the rudder correspondingly. Suitable mechanism enabling the rudder bar to be shifted for accommodating various leg lengths should be provided. It may include a bracket 10, secured to the upper end of tube 1, having integral with it a guide plate 11 extending fore and aft. A slide 2, generally of channel shape, is carried by guide plate 11 and the downwardly projecting flanges of the slide embrace opposite edges of such guide plate. This slide is integral with the tubular rudder bar 20, and is braced with respect to such rudder bar by gusset webs 21. The rudder bar can be displaced bodily in a fore and aft direction by movement of slide 2 along plate 11 to adjust the positions of the rudder pedals.

The rudder bar 20 may be held in the desired position of adjustment by a pin 22 seating in one of several holes 12 located at spaced intervals in the upper surface of guide plate 11. The head 23 of pin 22 is engaged over a lifter bar 24 having a slot 25 extending lengthwise of it, through which the pin 22 is inserted. The forward end of bar 24 is pivoted by a pin 26 to an upwardly projecting lug 13 carried by the forward end of guide plate 11. The rearward end of such bar is normally held down by a spring 27 to dispose the bar parallel to the guide plate. Lug 28 is secured to the lifter bar near its rearward end, to which may be attached a suitable tension element, such as light cable.

When it is desired to shift the rudder bar 20 forward or rearward lug 28 is raised to swing lifter bar 24 upward about its pivot pin 26. Such movement raises pin 22 to withdraw it from the hole 12 in which it was lodged. The slide 2 may now be shifted forward or rearward approxi-

ly the desired amount, whereupon the upward pull on lug 28 is discontinued. Spring 27 will then draw bar 24 downward, so that by shifting slide 2 slightly in one direction or the other pin 22 may drop into a different socket 12 to fix the relationship of the rudder bar 20 and bracket 10 in the newly adjusted position.

Such rudder bar position adjusting mechanism would create an additional complication if the pedals were mounted directly on the rudder bar, but my rudder pedal guide mechanism is equally effective where such an arrangement is used. Since the center of the rudder bar does not coincide with the axis of the upright shaft 1, as the rudder bar is swung in a clockwise direction as viewed in plan in Figure 2 it will be displaced bodily lengthwise to the right to a greater degree than if the shaft axis intersected the bar center, because of the orbital movement of the rudder bar center around the shaft. The degree of such lengthwise displacement for a given angular movement of the rudder bar will be amplified by adjustment of slide 2 forwardly along guide plate 11, and will be decreased as the slide is shifted rearwardly. Despite such lengthwise displacement of the rudder bar, however, my rudder pedal supporting and guiding mechanism constrains movement of the rudder pedals to a linear path in all swung positions of the rudder bar and in all adjusted positions of slide 2.

Each rudder pedal 3 is supported and guided for precisely linear movement by at least two sets of linkage, the movable end of each set being restricted to move in only a single plane. The movable ends of the particular linkages shown in the drawings are constrained to move only in vertical and in horizontal planes, respectively. The rudder bar 20, swinging about the vertical axis of tubular shaft 1, itself constitutes part of the linkage system the end of which is movable only in a horizontal plane. A link 30 has one end pivoted by a vertical joint or journal 31 to one end of rudder bar 20, and its other end pivoted by a vertical journal 32 to one end of rudder pedal spindle 36. If no other restraint were placed upon the rudder pedal than that imposed by link 30 and rudder bar 20 its spindle could assume any angular position in a single horizontal plane, and pressure on it in such plane would swing the rudder pedal about pivot 31 or 32 instead of swinging the rudder bar.

To the end of rubber pedal spindle 36 remote from pivot 32 linkage including links 33 and 34 is connected. These links are joined by a horizontal pivot 35 and the end of link 33 remote from link 34 is pivotally connected to rudder pedal spindle 36. The end of link 34 remote from link 33 is pivoted by a horizontal bolt to the standard 14 mounted rigidly upon floor 15 of the pilot's cockpit, or to an equivalent stationary support. Because the pivots 35 and 37 are horizontal, the end of link 33 remote from link 34 can move only in a vertical plane.

Since linkage 20, 30, 36, having vertical pivots, restrains movement of the joint between rudder pedal spindle 36 and link 33 to a horizontal plane, and since linkage 33, 34, having horizontal pivots, restrains movement of this joint to a vertical plane, such joint can traverse only a straight horizontal line defining the intersection of such vertical and horizontal planes.

It is further desired that spindle 36 should not swing in its horizontal plane, but always remain in an attitude perpendicular to its direction of movement in such horizontal plane thus estab-

lished by the vertical plane of linkage 33, 34. Consequently it is necessary that a journal parallel to pivots 35 and 37 of such linkage constitute this joint, instead of its being movable universally. Such journal insures that the spindle will remain perpendicular to its horizontal path of travel.

Two sets of linkages the movable ends of which move in intersecting planes will maintain linear movement of a rudder pedal or other element along the intersection line of the respective planes whether or not such planes are perpendicular. The more nearly such linkage planes approach mutual perpendicularity, however, the more effective and efficient will be the control of the movable elements if only two linkage systems are employed. While two linkages are sufficient for this purpose any number may be employed as long as all the lines of intersection of the respective planes in which the movable ends of such linkages move are parallel. Thus all such linkage movement planes may intersect in a single line, or two such planes in parallel relationship may intersect a third linkage plane in parallel lines, or two linkage planes inclined relative to each other may intersect a third such plane in parallel lines. Also it is immaterial how many links are employed in each linkage as long as they permit linear movement of the movable linkage end in its plane throughout the desired range of movement.

Consideration of the load distribution between the linkages of such a system is of importance. Particularly is this true where force applied to the guided element is to be transmitted to an anchor pivot of at least one of such linkages and converted into a torque acting on such pivot. In the instant case forward pressure on a rudder pedal produces a torque in shaft 1. In addition forces acting transversely of the direction of rudder pedal movement must be transmitted through the linkage system to the supporting structure. Thus the weight of the pedal, linkages, and the downward component of the pressure exerted by the pilot's foot is carried by the system.

When linkage such as 20, 30, 36, requiring that rudder pedal 3 move in a horizontal plane, is employed in conjunction with linkage such as 33, 34, movable in a vertical plane, all the vertical loads are carried by the former linkage. Instead of utilizing linkage movable in precisely a vertical plane to establish the direction of the horizontal line along which the rudder pedal must move, the plane of movement of linkage 33, 34 might be inclined although generally upright, as long as the direction of its line of intersection with the horizontal linkage plane is not changed. In such event the weight and other vertical loads would be carried partially by the latter linkage, the amount depending upon the degree of inclination from vertical.

Moreover, it is not even necessary that one of the linkage planes be horizontal in order to restrict an element supported by the linkages to horizontal movement, although such an arrangement is most convenient for airplane rudder operating mechanism of the general type illustrated. For other applications, if the movable end of one linkage moves in a plane which is not precisely vertical the most accurate control can be obtained by combining with such linkage another linkage which moves in a plane substantially perpendicular to the first. If such linkages are each disposed at an angle of 45 degrees to

vertical the gravity and other vertical loads will be shared equally by them. This load relationship will be preserved even though such inclined planes be disposed to intersect along a sloping line.

Although only one form of linkage and one type of application for such linkage is illustrated, it will be appreciated that the structure of the linkages and their arrangement may be varied widely while still being capable of guiding an element to move in a straight line and of carrying loads imposed on such guided element in directions transversely of its path of movement, as discussed above.

In Figure 3 the bearings by which pedal 3 is journalled on its axle 36 are conventional. Preferably journal 32 also includes antifriction bearings spaced at each side of the end of link 39 to prevent angular deflection of link 39 and rudder pedal spindle 36, and a similar construction is incorporated in pivot 34. The pivot of link 33 on rudder pedal spindle 36 is shown to include antifriction bearings, and the same construction may be used for pivots 35 and 37. While the bearing structure illustrated is very effective for preserving fidelity of movement when the guided element is subjected to heavy loads, it will be understood that the particular structure of such journals may be changed considerably, depending upon the requirements for each installation.

The mechanism described is all that is necessary to effect rotation of shaft 1 and consequent swinging of the rudder. Modern airplanes, however, are provided with wheel brakes which conventionally are operated by tilting the rudder pedal about a horizontal axis without swinging the rudder bar. Both the weight and forces for actuating such brake operating mechanism impose additional loads on the guided element. The brake operating mechanism may be of the hydraulic type, including a control valve 4 incorporated in the hydraulic brake system by conduits connected to openings in bosses 40 in customary fashion. One end of this valve is pivoted to a bracket 41, secured to the rudder pedal spindle 36 so that it cannot move angularly about the spindle's axis. The plunger 42 of valve 4 is pivoted to a lug 43 secured to the back of the treadle portion of the rudder pedal. As such treadle is tilted forward, therefore, plunger 42 will be shifted into the valve body to actuate the valve for applying the brakes.

I claim as my invention:

1. Airplane rudder pedal mechanism comprising a substantially horizontal rudder bar, pivot means supporting said rudder bar for rotation about its center, rudder pedals disposed generally parallel to the ends of said rudder bar at opposite sides of said pivot means, two horizontal links, each extending substantially perpendicular to said rudder bar and to said rudder pedals, and pivotally connected to one of said rudder pedals and to the corresponding end of said rudder bar to swing relative to both thereof about vertical axes, for restricting said rudder pedals to movement in a horizontal plane, two linkages, each supported by one end for movement confined to an upright plane generally perpendicular to said rudder bar, and pivot means connecting the unsupported ends of said linkages to said rudder pedals, respectively, to restrain movement of said rudder pedals transversely of said upright linkage planes and to guide them for movement, during swinging of the rudder bar, through positions

always parallel in the horizontal plane to which movement of said rudder pedals is restricted by said horizontal links and said rudder bar.

2. Airplane rudder pedal mechanism comprising a substantially horizontal rudder bar, pivot means supporting said rudder bar for rotation about its center, rudder pedals disposed generally parallel to the ends of said rudder bar at opposite sides of said pivot means, two horizontal links, each extending substantially perpendicular to said rudder bar and to said rudder pedals, and pivotally connected to one of said rudder pedals and to the corresponding end of said rudder bar to swing relative to both thereof about vertical axes, for restricting said rudder pedals to movement in a horizontal plane, two linkages, each supported by one end for movement confined to an upright plane generally perpendicular to said rudder bar, pivot means connecting the unsupported ends of said linkages to said rudder pedals, respectively, to restrain movement of said rudder pedals transversely of said upright linkage planes and to guide them for movement, during swinging of the rudder bar, through positions always parallel in the horizontal plane to which movement of said rudder pedals is restricted by said horizontal links and said rudder bar, locking means normally operable to maintain said rudder bar pivot means stationary, and releasing means operable to release said locking means for bodily shifting of said rudder bar along a path perpendicular to said rudder pedals into a different adjusted position, and said holding means being operable thereafter to maintain said rudder bar pivot means in such different adjusted position.

3. Airplane rudder pedal mechanism comprising a substantially horizontal rudder bar of considerable length, pivot means supporting said rudder bar for rotation about its center, rudder pedals disposed generally parallel to the ends of said rudder bar at opposite sides of said pivot means, each rudder pedal being located intermediate said pivot means and the adjacent end of said rudder bar, two horizontal links, each extending substantially perpendicular to said rudder bar and to said rudder pedals and pivotally connected to one end of said rudder bar and to the adjacent end of the adjacent rudder pedal to swing relative to both thereof about vertical axes, for restricting said rudder pedals to movement in a horizontal plane, two linkages, each supported by one end for movement confined to a vertical plane generally perpendicular to said rudder bar, and disposed close to said rudder bar pivot means, and pivot means connecting the unsupported end of each of said linkages, respectively, to the end of the adjacent rudder pedal remote from the connection of such rudder pedal to its horizontal link, to restrain movement of said rudder pedals transversely of said vertical linkage planes and to guide them for movement, during swinging of the rudder bar, through positions always parallel in the horizontal plane to which movement of said rudder pedals is restricted by said horizontal links and said rudder bar.

4. Linear movement crank mechanism comprising a horizontally swingable crank, link means having an end movable in a substantially horizontal plane and its other end pivotally connected to the swinging end of said crank, further link means having an end movable only in a substantially vertical plane and having its other end anchored to rotate about a horizontal 75 axis, and linearly movable operating means in-

terconnecting the movable ends of said two link means.

5. Linear movement crank mechanism comprising a horizontally swingable crank, further link means having an end movable in a substantially horizontal plane and its other end pivotally connected to the swinging end of said crank, and the other linkage having an end movable only in a substantially vertical plane and having its other end anchored to rotate about a horizontal axis, and linearly movable operating means such as a pedal rod interconnecting the movable ends of said two link means, the axis of swing of said crank being offset appreciably from the above-said vertical plane which is parallel to the line of said linear movement.

6. Linear movement crank mechanism comprising a horizontally swingable crank, a link having an end movable in a substantially horizontal plane and its other end pivotally connected to the swinging end of said crank, the body of said link being disposed normally substantially at right angles to the crank's moment arm, link means having an end movable only in a substantial vertical plane and having its other end an-

chored to rotate about a horizontal axis, and pedal rod means having pivotal joint means at opposite ends thereof, securing said link to such movable end of said link means, said pivotal joint means secured to said link means restraining movement of said pedal rod out of a position substantially perpendicular to the vertical plane of movement of such movable end of said link means.
